SAXOPHONE

Hugh W. Loney, Elkhart County, Ind., assignor to
 C. G. Conn, Ltd., Elkhart, Ind., a corporation
 of Indiana

Application August 31, 1934, Serial No. 742,291

6 Claims. (Cl. 84—385)

In saxophones, to effect the major trill, C to D, on C in the staff and on C above the staff, the present common practice is to play the D note too sharp, for all key mechanisms and devices heretofore invented have been so complicated that they have either not been used at all, or they have come into very limited use on saxophones. The principal object of my invention is to effect the major trill, C to D, by other and different means

10 than has been heretofore devised.

Another object of this invention is to provide improved and simplified means for effecting the major trill, C to D on C in the staff, and on C above the staff in a saxophone, this means comprising associated key mechanism for correctly sounding the high E-flat tone and for preventing flatness in the upper D note.

A third object of the invention is to provide improved mechanism for fractionally opening the E-flat tone hole to flatten the note D. Yet another object is to provide improved mechanism for fractionally opening the E-flat tone hole to flatten the note D for correctly sounding the latter, said mechanism comprising a tiltable arm for causing fractional opening of the E-flat tone hole, said tiltable arm being controlled by the rock shaft which carries the D key arm.

Other and more specific objects of the invention are mentioned and described herein.

30 The invention is illustrated in the accompanying drawings, wherein

Figure 1 is a semielevational view showing the invention applied to a saxophone and in which the E-flat tone hole is open fractionally and the 35 D tone hole is closed, and wherein the E-flat key arm is restricted by the stop arm;

Figure 2 is a similar view showing the same tone holes and the same elements and wherein both tone holes are wide open;

40 Figure 3 is a diagrammatic view or development of the key mechanism of a saxophone in which my invention is incorporated;

Figure 4 is a section taken on line 4—4 of Fig. 3 through the E-flat tone hole and including the 45 instrument body and the tampion;

Figure 5 is a section taken on line 5—5 of Fig. 3 through the D tone hole and including the instrument body and the tampion; and

Figure 6 is a section taken on line 6—6 of Fig. 3 50 through the F tone hole and including the instrument body and the tampion.

Similar numerals of reference indicate like parts throughout the several views on the drawings.

55 Referring now to the details of the drawings

the numeral 1 indicates a fragment of a saxophone body which is provided with tone holes 2 and 3 for producing the notes D and E-flat, respectively, said tone holes being under the control of the pads, or tampions, 4 and 5, respectively, said pads being mounted at the end of the tiltable key arms 6 and 7, respectively, Figures 1 and 2.

In this structure the key arm 6 is carried on a rock shaft 8 which is pivotally mounted in the 10 posts 9 and 10 fixed in the instrument body, the tone hole 2 being normally closed by the pad 4 due to the action of a spring 11 on the key arm 6. The key arm 7 is similarly mounted on a rock shaft 12 which is pivotally mounted in the posts 13 and 14 fixed in the instrument body. Key arm 6 is provided with an extension which carries the finger tip 15, and key arm 7 is provided with an extension 16 which carries finger tip 17 for depressing said arm, as is well known in the art. 20

The key arm extension 16 may be bent outwardly in relation to the instrument body 1 and the under surface thereof may be provided with a flattened surface 18, which may be termed a "wiper surface", for convenience, and which is 25 adapted to be normally engaged by the point of the wiper, or stop, arm 19 rigidly connected with the rock shaft 8 and extending radially from the latter. In Fig. 1 the wiper or stop arm 19 is engaged with the flat surface 18, thereby limiting the tiltable movement of the key arm 7; and in Fig. 2 the arm 19 has been tilted away from the surface 18, by rocking the shaft 8, thereby freeing the key arm 7 of said arm 19, whereby the tone hole 3 may be fully opened. 30

Obviously, when the arm 19 engages the flat surface 18 of key arm 7, thereby limiting the tilt of the arm 7, the key pad 5 which controls the tone opening 3 is only slightly lifted out of contact therewith, whereby said tone opening is only 40 partially opened. Figure 1 of the drawings also shows the tone hole 20 for producing note B, and the pad 21 for controlling same, the latter being in the closed position. Fig. 2 shows the tone hole 20 open, and both Figures 1 and 2 indicate the 45 adjacent button 22 which overlies the pad 21.

In trilling from C to D on both the conventional type of saxophone and a saxophone equipped with my invention the C note is played with the "forked" fingering, that is, by depressing the button 22 which overlies the pad 21 for the B tone hole. The button 22 is carried on the end of an arm 23 which is connected with rock shaft 24 and depression of said button rocks said shaft 24, thereby tilting an arm 25 connected therewith, 55

said arm 25 engaging beneath the extension 26 of a tiltable yoke element 27, said yoke element including the yoke arms 28 and 29 which are pivotally mounted on a hinge rod—not shown—well known in the art. An extension 30 of the yoke arm 29 carries a pad 31 which is adapted to open and close the tone hole which produces C# (sharp). It is therefore evident that depression of the button 22 depresses the yoke arm extension 30 and closes the tone hole controlled by the pad 31, which is conventional key mechanism now in common use on saxophones. The depression of the button 22, as above described, results in the opening of the C tone hole controlled by pad 32, which is not a part of this invention.

If now, the musician next plays the D of the trill by using the D key (pad 4) the D tone resulting therefrom is much too flat in both registers. It is therefore customary to use the E-flat key (pad 5) for playing note D. But in a conventional saxophone, which is not equipped with my invention, the upper note D, of the trill, is somewhat too sharp. To overcome this tone defect my invention is incorporated in the saxophone, and the important element of my invention is the stop arm 19 which normally contacts the flat face 18 of the key arm 7 to limit the area of opening in tone hole 3 when pad 5 is lifted therefrom when tone hole 2 is closed by pad 4. And it is this sharpness of the D tone, on the trill above referred to, which is fully overcome by the stop arm 19 which limits the area of the opening of tone hole 3, as above described, thereby flattening said D tone to the desired degree to produce the correct tone.

Also, when the tone hole 2 is opened by the depression of the key arm tip 15, which automatically tilts the stop arm 19 out of contact with the surface 18 of arm extension 16, the key arm 7 is then unrestrained, and depression of the tip 17 thereof fully elevates the pad 5 and fully opens the tone hole 3, thus sounding the high E-flat correctly.

It will be evident from the foregoing that my invention restricts the opening movement of the E-flat key pad 5 when the D pad 4 closes tone hole 2, thereby preventing sharpness of the upper note D of the trill, this being due to the fractional opening of the tone hole 3.

Also, it will be evident that, upon depression of the key arm 6 to open the tone hole 2 to produce D tone, the stop arm 19 is swung away from the flat surface 18 of the extension 16 of key arm 7, whereby depression of key arm 7, which actuates pad 5, enables the player to open tone

hole 3 to the maximum degree, thus sounding the high E-flat tone correctly.

I claim:—

1. In a saxophone, a saxophone body provided with a tone hole, a key arm and pad controlling said tone hole, means for limiting the movement of said key arm and pad for fractionally opening said tone hole, and means for relieving said key arm and pad of said movement limiting means to enable said tone hole to be fully opened. 10

2. In a saxophone, a saxophone body provided with a tone hole, a tiltable key arm and pad controlling said tone hole, means for limiting the tilt of said key arm and pad for fractionally opening said tone hole, and rock shaft means for 15 relieving said tiltable arm of said tilt limiting means to enable said tone hole to be fully opened.

3. In a saxophone, a saxophone body provided with an E-flat tone hole, a tiltable key arm and pad controlling said tone hole, tiltable means for 20 limiting the tilt of said key arm and pad for fractionally opening said tone hole, and means for relieving said tiltable key arm of said tilt limiting means to enable said tone hole to be fully opened. 25

4. In a saxophone, a saxophone body provided with a D note tone hole and an E-flat tone hole adjacent thereto, a tiltable key arm and pad controlling each of said tone holes, and means controlled by said D note key arm for limiting the tilt of said E-flat tone hole key arm. 30

5. In a saxophone, means for correctly sounding the D of the trill which may be sharp, said means comprising a saxophone body provided with a tone hole, a tiltable key arm and pad controlling said tone hole, a second tone hole located adjacent said first mentioned tone hole, a tiltable key arm and pad controlling said second mentioned tone hole, and means controlled by said second mentioned key arm for limiting the tilt 40 of said first mentioned key arm, whereby, upon tilting said first mentioned key arm, the tone hole controlled thereby is fractionally opened. 35

6. In a saxophone, means for correctly sounding the D of the trill which is normally sharp, said means comprising a saxophone body provided with an E-flat tone hole, a tiltable key arm and pad controlling said E-flat tone hole, a D tone hole located adjacent said E-flat tone hole, a tiltable key arm and pad controlling said D tone hole, and means controlled by said D tone hole key arm for limiting the tilt of said E-flat tone hole key arm, whereby, upon tilting said E-flat tone hole key arm, said E-flat tone hole is fractionally opened. 45 50

HUGH W. LONEY.
